[57] CLAIM

The ornamental design for a modular picture frame, substantially as shown and described.

DESCRIPTION

FIG. 1 is a front perspective view of a modular picture frame showing my new design, the side opposite being a mirror image; portions of the display area have been broken away for clarity of disclosure; and,

FIG. 2 is a perspective view of a modified form of the design shown in FIG. 1, the side opposite being substantially a mirror image.

The unshown bottom of the claimed design is substantially plain and unornamented.

FIG 2
